UNITED STATES PATENT OFFICE.

ASA E. SMITH, OF HILLSBORO, TEXAS.

LEVER-LATCH.

1,143,452.

Specification of Letters Patent. Patented June 15, 1915.

Application filed April 17, 1911. Serial No. 621,549.

To all whom it may concern:

Be it known that I, ASA E. SMITH, a citizen of the United States, residing at Hillsboro, in the county of Hill and State of Texas, have invented a new and useful Lever-Latch, of which the following is a specification.

This invention relates generally to hand levers such as are usually provided with notched segments and a latch to engage the segment and thereby lock the lever in any position to which it has been moved. Such levers are used for example on motor cars for shifting the transmission gear and for controlling the brakes.

The invention relates more specifically to the latch mechanism by means of which the lever is locked to the segment. So far as I am aware, this latch mechanism for locking the lever to the segment has consisted heretofore of a single latch which is intended to engage the teeth of the segment and which is released when desired by means of a suitable latch handle which is mounted upon the controlling lever. The disadvantages which I have discovered in a single locking latch are, first, that it does not permit a fine enough adjustment of the controlling lever, as said lever must necessarily be moved a distance from one notch on the segment to the next notch before it can be locked in position, and second, that if it should become broken, the efficiency of the controlling lever would be greatly impaired.

The object of the present invention is to overcome the disadvantages above set forth and this object is accomplished in the preferred form of the invention by means of a plurality of locking devices or latches mounted for independent operation upon the controlling lever, whereby any one of said latches can be caused to become engaged with the segment, it being preferable, although not essential to provide a common latch handle for releasing all of the latches.

A further object of the invention is to provide means whereby, without altering the usual arrangement of the notches or teeth in the segment, the controlling lever may be moved a distance which is either less or more than the distance between the two notches in the segment and then locked in position, this flexibility of adjustment be-

ing possible by the use of a plurality of locking latches, either one of which may be brought into action at will by the operator.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawing forming a part of this specification, Figure 1 is a side elevation of a controlling lever equipped with the improvement of the present invention; Fig. 2 is a sectional view taken at a right angle to Fig. 1 on a longitudinal line through the controlling lever; Fig. 3 is a view on an enlarged scale, in front elevation, partly broken away, showing a plurality of locking latches, the right hand latch being shown in its advanced position to engage one of the notches in the segment, the left hand latch, of course, resting on the high part of the segment between two notches; Fig. 4 is a section on the line Y—Y of Fig. 3; and Fig. 5 is a section on the line X—X of Fig. 3.

Like reference numerals indicate corresponding parts in the several figures of the drawings.

The controlling lever is indicated generally by the reference letter A and may be of any suitable form and construction. The lever A is fulcrumed at 1 and co-operates with the usual segment 2 formed with notches 3 intended to receive the latch of the controlling lever.

In carrying out the present invention I prefer to employ a plate 4 which is best shown in Fig. 2 of the drawing, and which is adapted to be bolted or riveted, as indicated at 5, to the lever A. The plate 4 is provided with upper guide means 6 and lower guide means 7 for the plurality of locking latches 8 and 9 which I propose to employ. The guiding means 6 and 7 may be formed either integral with the plate 4 or be otherwise held thereon in any suitable manner. The lower guiding means 7 preferably has a depending ear 10 which

serves in conjunction with the lower end of the plate 4 to straddle the segment 2 and thus hold the locking latches 8 and 9 in proper relation thereto, so that either one of said latches may slip into one of the notches 3. It will be understood, of course, that the locking latches 8 and 9 are arranged in such manner that it will be impossible for both of them to engage the segment at once, but 10 the operator can, of course, manipulate the controlling lever so as to cause either one of the locking latches to engage one of the notches in the segment. It will also be understood that while I have illustrated two 15 locking latches in the drawing, I am not to be limited to this number, as I may employ any desired number of latches according to the fineness of the adjustment to be secured.

Each of the locking latches 8 and 9 is 20 provided with a reduced upwardly extending stem 12 which passes through a suitable guide opening 13 in the upper guide means 6 of the plate 4 and is formed at its upper end with a longitudinal slot 14. Extending 25 through the longitudinal slots 14 of the stems 12 of the two latches 8 and 9 is what may be termed a stirrup member 15, the function of which is to release or withdraw the latches from their engagement with the 30 segment 2 when it is desired to move the controlling lever. The stirrup 15 at one of its ends is bent to form a loop 16 and the other end is shaped to form a resilient tongue or closure 17 for the loop 16. The 35 loop 16 is engaged with an eye 18 on the lower end of a releasing rod 19 which extends upward through a suitable ear or guide 20 and is connected at 21 with a latch handle 22 which may be of any suitable 40 form and construction, and preferably is pivoted upon the lever A, as indicated at 23.

The function of the slot 14, when in the 45 stems 12 of the two latches, is to permit movement of each latch independent of the other, and yet to cause the single stirrup member 15 to withdraw whichever one of the latches is in lowermost position. As shown in Fig. 1, the right hand latch, when it moves downward to engage one of the 50 notches, pulls the stirrup member 15 down with it. The slot 14 in the left hand notch, permits the stirrup member 15 to move downward in the manner indicated.

The means for positively throwing either 55 one of the latches 8 or 9 in engagement with one of the notches 3 of the lever 2 preferably consists of a coiled spring 24 which surrounds the stem 12 of each of the latches, said coiled spring bearing at its lower end 60 against the head of the locking latch, and at its upper end against the guide means or bridge 6, the tendency of the spring being to expand so as to normally force the latch with which it is connected downwardly, thereby 65 serving not only to throw the latch into en-

gagement with one of the notches 3, but also to hold the latch handle 22 in open position, as shown in Fig. 1.

The operation of the device is thought to be obvious. By manipulating the latch handle 22, whichever one of the latches 8 or 9 is in engagement with the segment 2 will be released. If it be then desired to move the controlling lever A a distance equal, say, to approximately half the distance between the notches 3, said lever is moved only far enough to let the other latch snap into the same notch. That is to say, as shown in Fig. 1, the right hand latch A is in engagement with a notch in the segment 2. By merely 70 operating the latch handle 22 to withdraw the right hand latch member from the notch of the segment, lever A can then be thrown a slight distance to the right, and the left hand latch 9 will snap into the same notch. On the other hand, supposing, with the parts shown in the position shown in Fig. 1, it is desired to move the controlling lever to the right a distance greater than one notch and less than two notches, it is only necessary to 75 release the right hand latch and move the lever A to the right, holding the latches in retracted position until the latch 8 has passed over the next notch to the right, at which time by releasing the handle 22, the 80 left hand latch 9 will snap into the notch of the segment 2 and lock the lever. 85

It is needless to say that the longitudinal slots 14 in the upper ends of the stems 12 serve to permit the latches 8 and 9 to move 90 relatively to the stirrup 15, so that one of said latches can be advanced when the other is retracted, as shown in Fig. 3.

The lever lock of the present invention is strong, simple, durable, and comparatively 105 inexpensive in construction, as well as thoroughly efficient and flexible in operation. Moreover, it is obvious that should one of the latches be accidentally broken at any time, the other latch could be used until the 110 broken one could be repaired.

What is claimed is:—

1. An attachment for segment levers comprising an elongated plate having longitudinally spaced guides, a pair of individually movable latches slideable in one guide and having stems slideable through the other guide, coiled wire expansion springs surrounding the stems and seating against the latches and last mentioned guide, the stems having elongated slots at that side of the last mentioned guide remote from the springs, and a loop shaped member engaged through the said slots. 115

2. An attachment for segment levers comprising a plate having a guide, a pair of spring pressed latches having stems slideable through the said guide, the latch stems having elongated longitudinal slots, and a loop-shaped member engaged through the slots 120

and having crossed arms, one arm terminating in a hook for engaging an actuating member, and the other arm projecting toward the bill of the hook to serve as a retaining element for holding the hook in engagement with the actuating member.

5 In testimony that I claim the foregoing

as my own, I have hereto affixed my signature in the presence of two witnesses.

ASA E. SMITH.
